UNITED STATES PATENT OFFICE.

IRWIN D. GROAK, OF CHICAGO, ILLINOIS.

DESIGN FOR A MOUNTING FOR WATER-PURIFYING APPARATUS.

Application filed January 24, 1928. Serial No. 25,009. Term of patent 3½ years.

To all whom it may concern:

Be it known that I, IRWIN D. GROAK, a citizen of the United States, and residing at Chicago, in the county of Cook and State of Illinois, have invented a new, original, and ornamental Design for Mounting for Water Purifying Apparatus, of which the following is a specification, reference being had to the accompanying drawing, forming a part thereof.

The figure is a perspective view of a mounting for water purifying apparatus, showing my new design.

I claim:

The ornamental design for a mounting for water purifying apparatus as shown.

Signed at Chicago, in the county of Cook and State of Illinois, this 24th day of December, A. D., 1927.

IRWIN D. GROAK.
